UNITED STATES PATENT OFFICE.

MARGOT LANDBERG, OF CHICAGO, ILLINOIS.

DESIGN FOR A FACE-SPRAYING DEVICE.

Application filed January 21, 1926. Serial No. 16,203. Term of patent 3½ years.

To all whom it may concern:

Be it known that I, MARGOT LANDBERG, a subject of the King of Sweden, residing at Chicago, in the county of Cook and State of Illinois, have invented a new, original, and ornamental Design for Face-Spraying Devices, of which the following is a specification, reference being had to the accompanying drawing, forming part thereof.

Fig. 1 is a front elevation of a face spraying device showing my new design.

Fig. 2 is a side elevation of the same.

I claim:

The ornamental design for a face spraying device, as shown.

MARGOT LANDBERG.
